(57) **CLAIM**

The ornamental design for an eliptical flushmount speaker, as shown and described.

DESCRIPTION

FIG 1 is a top plan view of a eliptical flushmount speaker showing our new design;

FIG. 2 is front view thereof;

FIG. 3 is a bottom view thereof;

FIG. 4 is a rear view thereof;

FIG. 5 is a right side view thereof; and,

FIG. 6 is a left side view thereof.

The broken line showing on the drawing disclosure is for illustrative purpose only and forms no part of the claimed design.
